UNITED STATES PATENT OFFICE

FRANK MONTES, OF NEW YORK, N. Y.

DESIGN FOR A CLOTHES HANGER

Application filed November 25, 1929. Serial No. 33,545. Term of patent 3½ years.

To all whom it may concern:

Be it known that I, FRANK MONTES, a citizen of Mexico, residing at New York, in the county of New York and State of New York, have invented a new, original, and ornamental Design for a Clothes Hanger, of which the following is a specification, reference being had to the accompanying drawing, forming part thereof.

Fig. 1 is a front elevational view of a clothes hanger, showing my new design.

Fig. 2 is a side elevational view of the same.

I claim:

The ornamental design for a clothes hanger, as shown.

In testimony whereof I have affixed my signature.

FRANK MONTES.
